Primary Examiner—Sandra L. Morris
Attorney, Agent, or Firm—Mila Shvartsman**[57] CLAIM**

The ornamental design for a game board, as shown and described.

DESCRIPTION

FIG. 1 is a front view of the rectangular board segment of the game board, showing my new design;

FIG. 2 is a front view of the arched board section thereof; and,

FIG. 3 is a front view of the boards together forming the game board.

The board is of conventional thickness, the rear being plain and unornamented.
